UNITED STATES PATENT OFFICE.

FREDERIC W. BROWN, OF TROY, AND THOMAS S. WILES, OF ALBANY, NEW YORK.

TELESCOPIC STAND-PIPE FOR EXTINGUISHING FIRES.

SPECIFICATION forming part of Letters Patent No. 423,663, dated March 18, 1890.

Application filed October 25, 1884. Serial No. 146,482. (No model.)

To all whom it may concern:

Be it known that we, FREDERIC W. BROWN, of Troy, Rensselaer county, New York, and THOMAS S. WILES, of Albany, in the county 5 of Albany and State of New York, citizens of the United States, have invented certain new and useful Improvements in Telescopic Stand-Pipes for Extinguishing Fires, of which the following is a specification, reference being had therein to the accompanying drawings.

This invention has relation to certain improvements in telescopic stand-pipes which are employed in connection with any suitable 15 water-supply for the purpose of extinguishing fires; and the invention has among its objects the provision of improved devices for supporting the stand-pipe when in use and for delivering water therefrom in desired directions and at desired angles.

Other objects and advantages of the invention will appear in the following description, and the novel features thereof will be specifically set forth in the claims.

25 Referring to the drawings, Figure 1 is a perspective of a stand-pipe constructed in accordance with our invention as it appears when in position for use in the extinguishment of a fire in a building. Figs. 2 to 5, inclusive, are enlarged details of the lower section and the adjacent parts of the stand-pipe. Figs. 6 to 8, inclusive, are enlarged details of the discharge pipe and nozzle and devices for directing and controlling the same; and Figs. 35 9 and 10 are a side and edge view, respectively, of one of the legs of the tripod employed. Figs. 11, 12, and 13 are details and modifications hereinafter described.

Like letters indicate like parts in all the 40 figures.

In this class of inventions the stand-pipe proper consists of a main or lower section A, intermediate sections B, and an upper or terminal section C, connected together telescopically, so that when water under sufficient head or pressure is introduced into the lower section the upper and intermediate sections are successively carried up by the pressure of the water, so that the stand-pipe can be elongated or elevated at will to any desired height, the upper section being provided with

a discharge-nozzle D, from which the water is discharged onto or into a burning building to extinguish a fire.

In our invention each of the sections of the 55 stand-pipe consists of a pipe fitted within the next lower section and provided with a packing, as B', Fig. 2, which is clamped against a flange B² by means of a packing-ring B³, which is screw-threaded to the lower end of 60 the pipe. The flange B² and packing serve to provide a water-tight joint between two of the sections.

Co-operating with the packing and flange just described is a short cylinder B⁴, screw-threaded into the upper end of the adjacent section, (B or A, as the case may be.) Riveted or bolted to the short section B⁴ are three or more straps E, the upper ends of which are angular and project inwardly, as shown at E'. 70 Between these straps and the section B is arranged a hoop F, the ends of which are projected parallel with each other, as shown at F', Fig. 3, and are embraced by the arms of a bifurcated handle G, said arms being cam or 75 wedge shaped, as shown at G', so that when said handle is vertical, as shown at Fig 2, the projected ends F'' of the hoop are separated from each other and the hoop loosely encircles the section, and when said handle is horizontal the said ends are compressed toward or against each other and the hoop snugly embraces the section which it encircles and prevents its longitudinal movement in the adjacent section. The function of the handle 80 and hoop is to secure the sections in an elevated position just before they and the next lower section are raised by the pressure of the water, as before described. The handle of each section is forced to a horizontal position, and as each ring and handle reaches the lower section during the process of lowering the stand-pipe its handle is turned to a vertical position, in order that the next section above may be lowered into its adjacent section below, so that when the apparatus is 85 completely lowered and ready for transportation the length thereof is that of the lower section in addition to the lengths of the successive straps of the additional sections. We 90 do not herein claim these clamping-rings and their adjacent devices, as they, in connection

with other features herein, are made the subject-matter of a previous patent, No. 306,575, granted October 14, 1884, to one of us.

In this instance we have devised novel features of construction in the device by which the stand-pipe is supported and adjusted, as well as novel features of construction in the discharge-pipe, and in the devices for controlling the same and novel improvements in the clamping-rings.

Referring more particularly to Figs. 1 and 2, it will be seen that at the upper end of the main section A, and encircling the same, there is secured a casting H, which has an annular flange H', the lower surface of which is convex, said flange being united to the cylindrical portion H² by webs, as clearly indicated in said figure. Encircling the section A, just below the casting H and coming in contact therewith, is another casting I, the cylindrical portion of which is flared outwardly from the cylinder, and the flanged portion I' of which is concave at its upper surface to agree with or fit the convexity of the casting H. The casting I is provided with lugs I², transversely perforated for the pivotal connection of the tripod-legs J, as hereinafter described. Now, it will be noticed that the upper casting, being fixed to the lower section and resting within the concavity of the lower casting, said section, together with those contained therein, when supported on the tripod, as shown in Fig. 1, is suspended and is capable at its lower end of swinging in all directions, whereby it may be positively inclined, so as to project the upper sections in any desired direction; or it may be (when said sections are inclosed within the main section) allowed, by the action of gravity alone, to assume a truly vertical position, and this notwithstanding the contour of the ground upon which the tripod stands and notwithstanding the arrangement of the legs of the tripod. We consider this means of supporting a stand-pipe as one of the important novel features of our invention, and we consider the two castings above described, which serve to support the stand-pipe, as and define the same to be a "bowl-joint," being after the nature of a ball-and-socket joint.

Referring to Figs. 8 and 9, although each of the legs of the tripod may be of any usual construction and in any manner adapted for connection with the casting I, in this instance for strength and cheapness we employ a main portion J of wood, having a casting J', adapted to embrace the wood at its upper end, provided with an eye J² and adapted to enter between the lugs I², when a bolt, rod, or pivot is passed transversely through all, so as to form a hinge-joint. A ferrule or casting J³, provided with a spike or point J⁴, is secured in any suitable manner to the lower end of the main portion of the leg. Near the lower end of the wooden portion there is formed a slot J⁵, passing therethrough, in which is an eccentric button J⁶, which serves to securely

hold a guy rope or cord J⁷, which passes through said slot and is suitably connected to the lower end of the main section. There being a cord J⁷ for each of the legs, it will be seen that when the section has been adjusted to a desired position it may be retained in said position by means of the guys. Above the button J⁶, and at the side of the main portion of the leg, is secured another eccentric button J⁸, which operates in connection with a bracket J⁹ to securely hold a guy J¹⁰, (of which there are three,) that extends from the leg to near the upper end of the upper section, or it may be to an adjacent part of the discharge-pipe, so that by the use of the guys J¹⁰ the stability and firmness of the stand-pipe when extended are assured. The lower end of the main section A is provided with a series of valves A', having communication through suitable ports or openings A² with the interior of the section. The said valves are screw-threaded, as at A³, for the reception of the ordinary coupling used upon hose, so that water may be supplied through said hose either from a hydrant or a steam-pump or fire-engine, or other source of supply. Eyes A⁴ are provided for securing the guys J⁷ to the lower portion of the main section. 95

Referring to Figs. 6, 7, and 8, it will be seen that the upper section C terminates or is provided with a casting C', having an annular flange or shoulder C² and a cylindrical extension C³. Upon the shoulder C² is rigidly secured a ring C⁴, having an upwardly-extended bracket C⁵, which serves as the support for a pin or stud C⁶, upon which is mounted, rotatably, a beveled gear C⁷ and a belt or rope pulley C⁸. Within the cylindrical portion C³ of the casting C' is a short cylinder K, having an exterior annular flange K'. Over this flange is fitted a sleeve K², which is interiorly screw-threaded for connection with the upper end of the casting C', whereby a water-tight joint is made between the cylinder and the casting, and yet a joint which enables the rotation of the cylinder (and of the parts mounted thereon) within the extension C³. Furthermore, this construction facilitates the assemblage of parts in operative position, as shown, and the separation thereof. Embracing the upper portion of the cylinder K is a horizontal beveled gear L, which is secured rigidly to the cylinder by a set-screw L', or it may be by any other well-known equivalent device. The cylinder K projects slightly above the gear L, and is screw-threaded for the reception of an interiorly screw-threaded cap-piece M. The cap-piece is centrally and longitudinally bored to agree with the internal bore of the cylinder K, and is transversely bored, as at M', in tapering form, to receive the discharge-pipe N, which is finished exteriorly to fit the transverse bore of the cap-piece. The discharge-pipe is provided with a port N', which communicates with the bore of the cap-piece when the discharge-pipe is in a certain position, as hereinafter described. The body por-

tion of the discharge-pipe, after passing through the cap-piece, has a quarter-bend, and to its end is secured in any suitable manner the discharge-nozzle D. The opposite end 5 of the discharge-pipe is provided with a rigidly-mounted belt or rope pulley O, to which is attached a counter-weight O', the function of which is to counterbalance the weight of the discharge-nozzle. The port N' is arranged 10 with relation to the quarter-bend of the discharge-pipe, so that when said bend points in a direction opposite that shown in Fig. 8 said port comes in contact with a solid portion M² of the cap-piece and the escape of water therefrom is prevented; but when the discharge-pipe and nozzle are rotated so as to be in other 15 positions than that mentioned a free passage of water is had through the port. By controlling the position of the discharge-nozzle 20 by means of a hand-rope P, passing over the pulley O to the ground, the discharge of water may be interrupted at will without manipulating the valves A' at the base of the stand-pipe, and by the same means—that is, 25 by the rope P—any desired inclination of the discharge-nozzle can be secured. By the use of a similar rope Q, passing over the pulley O⁸ and to the ground, the gear C⁷, meshing with the gear L, may be rotated, so as to rotate 30 the cap-piece, the discharge-pipe, and the nozzle, so that said nozzle may be directed to any point in a horizontal plane, and therefore by means of both ropes a stream of water delivered from the discharge-nozzle may be 35 directed to any desired point.

We do not wish to be understood as limiting our invention to the exact details of construction herein shown and described, but reserve the right to alter the same in any manner 40 and to any extent within the skill of persons conversant in the construction of similar apparatuses.

If desired, an additional guy J¹⁰ may be secured to the discharge pipe or nozzle or to 45 the cap-piece or to the upper end of the upper section in such a position as to resist the reaction of the outgoing stream of water, and, as before stated, one of the guys J¹⁰ may be arranged in a position to perform this function.

By reference to Figs. 1 and 11, an additional device for holding the main section steady and firm will be seen—namely, the steady pin or stake R, which is fitted in the plug or 55 head of the section, so as to be capable of longitudinal movement after the manner of a piston-rod and is provided with a head R' serving the function of and similar to a piston-head. Between the head R' and the 60 plug and encircling the stake is a coiled spring R², which serves to normally hold the stake with its point or outer end in close proximity to the end of the section. When the lower section has, by gravity or otherwise, 65 been brought to a desired position, the admission of water therein acts by pressure upon the head R' to force the pin outwardly against

the tension of the spring until its point comes in contact with or penetrates the ground and is held in that position so long as a supply of 70 water is maintained in the pipe.

As heretofore stated, we do not claim in this application the specific construction of the clamping-rings F; but we illustrate a different form of clamping devices in Figs. 12 75 and 13, which we consider preferable to, as well as interchangeable with, the construction hereinbefore described. In this modification instead of the straps E, secured to a section, as B, we employ a casting S, into which the 80 section is screw-threaded or in some other well-known manner connected with the casting, said casting being provided with lugs S', arranged diametrically opposite each other. The clamping-ring F is formed in two sections, each semicircular and provided with projecting ends adapted to be clamped and bound by the hand-lever G, the pin or bolt S² being passed through the bifurcated arms of the handle, through the ends of the semicircular straps, and through the lugs S', to bind the parts together, when by manipulating the handle, as before described, the semicircular straps are made to bind upon a section working telescopically in the casting S and the 95 section to which it is attached.

Having described our invention and its operation, what we claim is—

1. In a telescopic stand-pipe, and in combination with the lower section thereof, a rigidly-secured collar having a lower convex face and a removable collar having an upper concave face, an outwardly-flared body portion, and lugs for the reception of supporting devices, substantially as specified. 100

2. In a telescopic stand-pipe, a lower section provided with a collar having a lower convex face and cylindrical portion, combined with a removable collar having an upper outwardly-projecting concave face and an 110 outwardly-flared dependent body portion, and integral lugs connecting said concave and body portion and transversely perforated for the pivotal connection of tripod-legs, substantially as described.

3. In a stand-pipe of the class described, a tripod, a section mounted thereon by a bowl-joint, and a series of guy-ropes extending from the bottom of the section to the legs of the tripod, substantially as specified. 120

4. The combination of the upper section, a removable cap-piece connected therewith and having a transverse tapered bore, a discharge-pipe having a quarter-bend and tapered portion fitting said bore and extending through 125 the cap-piece, and a pulley on said extended portion of the discharge-pipe, substantially as described.

5. The combination, with the upper section and a cap-piece centrally and longitudinally bored and transversely bored in tapering form, of a quarter-bend discharge-pipe having tapered portion fitting the tapered bore 130 of the cap-piece and extending therethrough,

- a pulley on the extended end of said pipe, and a rope passing over and attached to said pulley and extending to the ground, substantially as and for the purpose specified.
- 5 6. The combination a cap-piece, a discharge-pipe rotatably mounted therein, a pulley mounted upon the discharge-pipe, and a counter-weight secured to the pulley, substantially as specified.
- 10 7. The combination of the section C, the cylinder C', the bracket C⁵, the sleeve K³, the cylinder K, having the flange K', the gears C⁷ and L, and the pulley C⁸, substantially as shown and described.
- 15 8. The combination of the transversely-bored closed cap-piece M with the quarter-bent discharge-pipe N, mounted in said bore, having the single port N', located to come in contact with the solid portion M² of the cap-piece, and the pulley O on the discharge-pipe, having counter-weight O', substantially as shown and described.
- 20 9. The combination of the cap-piece M, the discharge-pipe N, the discharge-nozzle D, the pulley O, and the rope P with the cylinder K, sleeve K², the gears L and C⁷, the pulley C⁸, the brackets C⁶, and the section C, substantially as shown and described.
- 25
10. In a stand-pipe, the combination, with the lower end of the same or of the lowest section thereof, of the longitudinally-removable steadyng pin or stake, substantially as specified.
11. In a stand-pipe, the combination of a lower section and a longitudinally-removable steadyng-pin having a head arranged within the section to receive pressure from the water therein, substantially as and for the purpose set forth.
12. The combination of the section A, the pin or stake R, having the head R', and the coil-spring R², substantially as shown and described.
13. The combination, with a section B, of the casting S, having the lugs S', the semicircular clamping-straps F', and the bifurcated handle G, substantially as shown and described.
- 40 45
- In testimony whereof we affix our signatures in presence of two witnesses.
